UNITED STATES PATENT OFFICE.

NANCY L. OZMUN, OF CLEVELAND, OHIO.

HAIR-CURLER.

1,064,084.

Specification of Letters Patent. Patented June 10, 1913.

Application filed February 17, 1913. Serial No. 748,779.

To all whom it may concern:

Be it known that I, NANCY L. OZMUN, a citizen of the United States, residing at Cleveland, in the county of Cuyahoga and State of Ohio, have invented a new and useful Improvement in Hair-Curlers, of which the following is a specification, the principle of the invention being herein explained and the best mode in which I have contemplated applying that principle, so as to distinguish it from other inventions.

My invention has reference, as the title implies, to an improved hair curling appliance.

The various hair curlers heretofore marketed have each presented, along with distinct features, (patented or otherwise) each its own disadvantages outweighing in relative importance any advantages attained by one or more of such features. In consequence, no single curler has drawn to itself a major share of commercial favor. I should here add that I am thoroughly familiar among others with the Letters Patent numbered 122,183, 672,506, 709,959, 710,702, 720,726, 762,246, 897,323, 909,979, 13,442, issued respectively to Mayer, Godward, Klarson, Martin, McCarthy, McIntire, Taylor, Goldner, Davis.

Accordingly, my primary object has been to contrive a hair curler which shall more closely approach a practical consummation in the art.

More specific objects may be enumerated as follows: the provision of a device of the character stated which while simple of manipulation, will be truly efficient, may be readily removed without entangling, will furthermore afford absolute comfort to the wearer by reason of combining the qualities of softness, lightness, flexibility, yieldingness and elasticity, and besides be simple, durable and economical of manufacture.

The inventive conception is embodied in means which are hereinafter explained and variously combined in the claims, while the annexed drawing and particular description thereof together set forth in detail several certain means constituting my invention, the disclosed means however, being but some of various mechanical forms in which the principle of my invention may be applied.

Figure I is a normal plan of a hair curler embodying the preferred form of my invention. Fig. II is a side elevation of Fig. I. Fig. III is a perspective view looking in the

direction of the arrow represented in Fig. II. Fig. IV is a perspective showing the application of my curler to a lock of hair. Fig. V is a perspective of a modified form. Fig. VI is a perspective of a second modification.

I choose to manufacture my invention from a single piece of high grade rubber. The structure depicted in the drawing comprises two primary parts. These I term a core portion and a flap portion and they are consistently designated respectively by the reference characters A and B.

The core portion A is intended to exercise its function while inclosed by a lock of hair which has been manually coiled about it. This portion A is preferably tubular in formation, as indicated by the opening a', of circular cross-section and is closed at its free extremity. Here it is fashioned as a knob a² which constitutes one of two complementary parts of a well-known fastening arrangement. The thickness of the rubber of the portion A should not be great, say one thirty-second ($\frac{1}{32}$) of an inch in order to satisfy the requirements earlier put, namely softness, lightness, flexibility, yieldingness and elasticity.

The flap portion B in the exemplification shown appears somewhat longer than the portion A. It is a continuation of a smaller portion of the lateral or peripheral surface of the portion A, such that it is necessarily and purposely a concavo-convex surface or of arcuate cross-section. Near the extremity of the portion B a pair of eyelets b' are provided. These are intended for the reception singly of the knob a' as will be presently manifest.

After a specific refractory lock of hair has been grasped and wound around the core portion A, the flap portion is in turn wound around the hair in the reverse direction as clearly shown in Fig. IV. Thereafter the two extremities are fastened by pressing the knob a' through one or the other of the openings b'. Mention should be made of the fact that a better bite upon any portion of the lock of hair is obtained by a flap having its inner or under side concave than would be the case if the flap proper were flat. A somewhat similarly desirable and efficacious binding effect upon the hair against the core may be obtained by stretching the flap preparatory to winding by which a constricting force is exerted tending to partially collapse

the core A and thus the more surely preclude sliding of the hair strands in a longitudinal direction between the core A and flap B. Procedure after the manner of this last mentioned suggestion, also permits a closer overlapping on the part of distinct convolutions, owing to the increased operative length of the flap. The tighter binding effect produced in this wise serves to impress the desired curling effect in a more efficacious manner as will be readily understood. Furthermore, the smooth surface which my curler presents throughout assists toward an easy manipulation, and precludes likelihood of disrupting the finished curl due to entangling while it is being unfastened. The hollowness of the elastic core portion in the meantime insures not only the qualities of lightness and yieldingness, but flexibility and even collapsibility to an extent which readily permits the whole to adapt itself readily and without pressure to the various contours presented by different parts of the head to which it is secured. My curler itself is also, by reason of the elasticity of its core portion, less apt to hunch or lump together and the lineal extent of the particular lock of hair may in consequence be substantially maintained as an advancing spiral and not permitted to slip upon the core portion. These become dominant factors of merit as regards comfort when the wearer prefers to have the curlers attached, during sleep or at any other time while the head is reclined in such a position that pressure is applied against the curler.

The modification to which Fig. V gives emphasis, resides in having a more or less flattened hollow core portion A and really flat flap portion B. The modified form seen in Fig. VI merely alters the type of complementary fastening contrivance upon respective ends of the curler, to the common type of glove snap. These metal elements a^3 and b^2 may be attached in any feasible manner, being suggested as alternative because of possible individual preference therefor.

My invention being thus described with sufficient thoroughness, what I desire to secure by Letters Patent and therefore claim 50 specifically, is:

1. A hair curler formed of a single piece of rubber and comprising a hollow collapsible core portion and a thin elongated flap portion forming a continuation of one surface of said core portion at one end thereof, the free extremities of said portions being provided with complementary fastening contrivances. 55

2. A hair curler formed of a single piece of rubber and comprising a tubular core portion having one extremity closed, and a flap consisting of a thin strip of arcuate cross-section extending from the opposite end of the tube and adapted to be wound about the 65 same. 60

3. A hair curler comprising a hollow core member, said core member being flexible, and an elastic flap member of arcuate cross-section and forming a continuation of said 70 core member, and means for fastening extremities of said portions to each other. 75

4. A hair curler comprising a flexible tube, and an elongated flap of arcuate cross-section adapted to be wound about said tube, the concave surface of said flap being nearest the axis of said tube, the free extremities of said tube and flap being provided with complementary fastening contrivances. 80

5. A hair curler comprising an elastic 80 tube, one end of said tube being closed to form a knob; and an elastic flap extending from the open end of said tube and adapted to be wound around the same, said flap being of arcuate cross-section throughout its entire length, the free extremity of said flap being provided with a plurality of eyelets adapted to coöperate with said knob. 85

Signed by me, this twelfth day of February, 1913.

NANCY L. OZMUN.
